UNITED STATES PATENT OFFICE.

JAMES EDWIN PHILLIPS, OF NEW YORK, N. Y.

WINDOW-LOCK.

1,311,708.

Specification of Letters Patent.

Patented July 29, 1919.

Application filed February 6, 1919. Serial No. 275,421.

To all whom it may concern:

Be it known that I, JAMES EDWIN PHILLIPS, a citizen of the United States, and a resident of the city of New York, borough 5 of Manhattan, in the county and State of New York, have invented a new and Improved Window-Lock, of which the following is a full, clear, and exact description.

This invention relates to window locks 10 and has for an object the provision of an improved construction which is simple and strong and formed so as not to readily get out of order.

Another object in view is to provide a simple construction which may be easily operated interiorly, but will not be readily observed from the exterior of the window.

In the accompanying drawing:

Figure 1 is a front view of a window and 20 part of a surrounding wall together with an embodiment of the invention shown applied to the window.

Fig. 2 is an enlarged fragmentary front view of part of the window shown in Fig. 1 25 with a lock embodying the invention shown applied thereto.

Fig. 3 is a section through Fig. 2 on line 3—3.

Fig. 4 is a detail fragmentary sectional view through Fig. 2 on line 4—4.

Referring to the accompanying drawing by numerals, 1 indicates an ordinary wall provided with a window frame 2 in which sashes 3 and 4 are positioned, said sashes 35 sliding up and down in the usual manner. Ordinarily heretofore most windows are provided with a lock arranged centrally on the transverse bar 5, but in the present invention it is aimed to provide either one or 40 two locks at the ends of bar 5.

As shown in Figs. 2 and 3 the upright 6 of the upper sash 3 is provided with a plate 7 held in place by screws or otherwise, said plate having a socket 8 for receiving the 45 bent end 9 of the locking bar 10. This locking bar is provided with a horizontal section 11 fitting between the uprights 12 and 13 of the retaining plate 14. This retaining plate is connected with the upright bar 15 of the 50 sash 4 by any desired means, as for instance screws. From the horizontal section 11 of the locking bar 10 a flaring locking handle 16 projects, said handle being positioned beneath the hook 17 when the parts are in a 55 locked position. By pressing down on the

outer end of the handle 16 and then laterally the rocking bar may be moved from beneath the hook 17 and then removed from the retaining plate 14 and also plate 7, so that the sashes will be released and may be freely 60 moved up and down as desired.

It will, of course, be evident that the handle 16 is resilient, though sufficiently stiff to lock the parts in position when interlocked with hook 17 so that there can be no independent up or down movement of either of the sashes.

What I claim is:

1. A locking device for windows comprising a plate having a socket therein adapted 70 to fit into an upper sash, a plate having a groove therein adapted to fit into the top of the lower sash of a window, a locking bar having a bent section for fitting into said socket and a horizontal section fitting into 75 said groove, said locking bar being positioned so that the upper part will fit flatwise against the face of the upper sash and the lower part will fit flatwise against the face of the lower sash, and means arranged 80 in the lower sash for locking said bar against accidental removal.

2. In a window lock the combination with upper and lower sashes of a plate having a socket therein for the upper sash, a grooved 85 member connected with the upper part of the lower sash, said grooved member being arranged in a horizontal plane, a substantially Z-shaped locking bar with the center fitting into said grooved member and one 90 end fitting into said socket member, said locking bar being positioned so that the upper part will fit against the face of the upper sash and the lower part will fit against the face of the lower sash and a hook engaging 95 the opposite end to that fitting into said socket member for holding the locking member normally in said socket member and said grooved member.

3. In a locking device for windows the 100 combination with upper and lower sashes of a window of a locking bar arranged exteriorly of said sash formed with a central section adapted to fit against the top of the lower sash, and a pair of end sections, one 105 end section extending along the upper sash and the other end section along the lower sash, a socket member overlapping the end of the locking member extending along the upper sash, means connecting the socket 110

member with said upper sash, and a hook normally overlapping the end of the locking member extending along the lower sash.

4. In a lock for windows the combination with an upper and lower sash of a socket arranged in the upper sash near the lower part thereof, a hook arranged in the lower sash near the upper part thereof, and a bodily removable substantially Z-shaped locking member having one end bent for fit-

ting into said socket and the other end bowed outwardly so that when it is forced into said hook it will have a tendency to remain therein, the central section of said locking member resting on top of the lower sash whereby said sashes cannot move independently, said locking member being positioned exteriorly of the sashes.

JAMES EDWIN PHILLIPS.
